SLAB AND FLOOR

George L. Rackle, Cleveland, Ohio, assignor to
The Geo. Rackle & Sons Co., Cleveland, Ohio,
a corporation of Ohio

Application June 13, 1939, Serial No. 278,877

3 Claims. (CL 72—68)

This invention relates to an improved building slab and floor structure, an object of the invention being to provide an improved structure which will present a strong formation when built into a floor.

Another object of the invention is to provide a floor slab which is of a size to be readily handled and which is so formed that when placed in the floor it is readily interlocked with adjacent slabs to form a complete floor.

A further object of the invention is to provide an improved slab and floor structure wherein the slabs are reinforced individually and grouting as well as reinforcing materials are arranged between the respective slabs to provide a proper connection between the slabs.

In the accompanying drawings—

Fig. 1 is a sectional view through part of a floor disclosing certain features of the invention;

Fig. 2 is a perspective view of part of one of the slabs shown in Fig. 1, certain parts being broken away for illustrating the reinforcement;

Fig. 3 is a top plan view of part of the structure shown in Fig. 1, certain parts being broken away for illustrating certain bonding and anchoring members; and

Fig. 4 is a sectional view through Fig. 3 approximately on the line 4—4.

Referring to the accompanying drawings by numerals, 1 indicates the flooring as a whole and 2 a slab. The slab 2 may be of any desired length and also of any desired width. However, it has been found that a desired width for the slab is twenty-four inches while the depth is approximately six inches at the sides and approximately two inches at the center. A desired length for most uses is sixteen feet. A slab of this size presents a unit designed to carry light house loads. While the dimensions given have proved satisfactory for many uses, it will be understood that the slab may be larger or smaller without departing from the spirit of the invention.

As illustrated particularly in Figs. 1 and 2, the slab 2 is provided with a center 3 which is flat and straight when properly cured and set. The upper surface is hard trowelled to provide a desired appearance and surface. The center part 3 is preferably of the same thickness throughout and merges into depending edge members 4 and 5 which are identical in construction. A metal reinforcement 6 is provided for the slab, said reinforcement including a loose woven metal framework 7 and a pair of comparatively large

strong bars 8 and 9 extending through the respective edge members 4 and 5. It will be understood, of course, that the reinforcement 6 is placed in a suitable mold and concrete is cast around the same.

In forming the slab 2 each longitudinal edge is provided with an offset 10 whereby laterally contacting longitudinal beads or extensions 11 will be presented. Also there is provided a groove 12 in each of the offsets 10. By this construction when two or more of the slabs are in use, as shown in Fig. 1, the beads or extensions 11 come together but preferably a small layer of cement is arranged therebetween.

When the parts are arranged as shown in Fig. 1, grooves are presented in which suitable grouting material is placed that acts to provide a suitable joint between the side edges of the respective slabs. If desired, a pipe 15 may be embedded in the grouting 14 for the reception of telephone wires or other articles as desired. Where the ends of two slabs 2 are supported by a beam 16, as shown in Fig. 4, a continuity rod or bar 17 is positioned preferably centrally of the grouting 14, though if desired it could be arranged in one of the semi-circular grooves 12. By reason of the semi-circular grooves 12, the grouting presents a strong key for locking the parts together. Also, if desired, end anchoring members 18 could be provided. After the grouting 14 has been placed in position it is trowelled down smoothly and evenly with the adjacent slabs so that a continuous even flat floor will be provided.

As the slabs 2 are preferably comparatively narrow and comparatively short they may be readily handled by workmen and as they are preformed a few workmen may quickly lay or build a floor that will be strong and will present a neat appearance. In view of these facts it will readily be seen that the ease of handling and the simplicity of the structure results in a low cost of production and at the same time presents a floor structure in which continuity bars may be placed as desired. Also by reason of the fact that the slabs may be grouted together along longitudinal lines, strains will be readily conveyed to adjoining units which result in presenting a strong floor with a minimum amount of material. The respective slabs 2 are perfectly straight and true and the upper surface of each slab is hard trowelled and the joining is first grouted and then pointed with any colored mortar and struck smooth as in case of Spanish floor tile. The respective slabs will be slightly cambered or crowned when cast from one end to the center to com-

pensate for the shrinking of the grouting when it is thoroughly cured. When the respective units or slabs are cured they will be straight and the floor will be straight and flat.

5 By reason of the construction presented if light-weight aggregate in the grouting is used, the weight is maintained at a minimum for a given strength of floor. Also by reason of the provision of the grouting not only may the separate units be almost integrally connected but means are provided for running wires through the center of the ceiling or across the floor without injuring the slabs.

10 I claim:

15 1. A concrete floor slab, including a metallic reinforcement having a foraminous flat metal body and depending foraminous side walls for the full length of the body and a stiffening bar independent of and spaced from said foraminous body arranged adjacent the lower edge of each of said side walls for the full length of the side walls and a body of concrete embedding said reinforcement, said concrete body having a substantially straight flat central portion and a pair 20 of depending side members, the bars of the reinforcement being arranged in the lower part of said depending side members, each of said depending side members being formed with a rectangular longitudinally extending projection at 25 its lower edge and a longitudinally extending groove between the projection and the surface of the slab in each depending side member.

30 2. A floor of the character described, including a plurality of slabs arranged side by side, 35 each of said slabs being formed with notches

which form grout-receiving grooves when the slabs are arranged side by side, a supply of grouting material arranged in each of said grooves and continuity bars arranged in said grooves and embedded in said grouting material, said continuity bars functioning to lock slabs together end to end while said grouting material functions to lock the respective slabs together edge to edge.

3. A reinforced concrete floor slab including a concrete body and a metal reinforcement extending throughout said concrete body, said metal reinforcement comprising a rectangular wire mesh flat body having depending side walls on each longitudinal side edge of said flat body and a reinforcing metal bar extending along but spaced from the bottom edge of each of said depending side walls, each of said bars being strong and large in comparison to the wire mesh, said concrete body encasing said wire mesh body and said bars, said concrete body having a rectangular flat central portion and a depending portion along each longitudinal side edge of said concrete body, each of said depending portions having one of said bars embedded therein near its lower edge, each of said depending portions having a longitudinally extending offset, a longitudinally extending groove intermediate the height of the offset, and a rectangular bead extending laterally from the longitudinal edge whereby when two slabs are placed in contact side by side said beads will engage and the offsets of the respective slabs will form a grout-receiving recess.

GEORGE L. RACKLE.
